DESIGN FOR A SHOE HEEL

William E. Kavenagh, Windsor, Vt., and Harry L. Post, Akron, Ohio, assignors to Wingfoot Corporation, Wilmington, Del., a corporation of Delaware

Application February 3, 1940, Serial No. 89,991

Term of patent 7 years

To all whom it may concern:

Be it known that we, William E. Kavenagh and Harry L. Post, citizens of the United States, residing, respectively, at 38 Ascutney Street, Windsor, in the county of Windsor and State of Vermont, and 686 Sunnyside Avenue, Akron, in the county of Summit and State of Ohio, have invented a new, original, and ornamental Design for a Shoe Heel, of which the following is a specification, reference being had to the accompanying drawing, forming part thereof.

Fig. 1 is a bottom plan view of a shoe heel showing our new design, and

Fig. 2 is a section on the line 2—2 of Fig. 1.

We claim:

The ornamental design for a shoe heel, as shown.

WILLIAM E. KAVENAGH.
HARRY L. POST.
